5 Claims. (Cl. 121—38)

1

The invention relates to an adjustable propeller plant.

In known plants in which the servomotor is built into the propeller shaft a supply sleeve sealed by stuffing-boxes is provided for the supply of pressure medium to the servomotor. These stuffing-boxes are thus under the high supply pressure of the servomotor pressure medium and losses of pressure medium are inevitable.

In order to eliminate this disadvantage the present invention provides a servomotor for adjusting propeller blades during service which, while turning with the propeller shaft and operated by pressure medium, is arranged in an enclosed stationary casing sealed at the outlet opening for the propeller shaft.

An embodiment of the invention is shown diagrammatically in the drawing.

Fig. 1 shows a longitudinal section through the casing surrounding the servomotor.

Fig. 2 a cross-section on the line II—II of Fig. 1.

Fig. 3 a longitudinal section through the servomotor and the control members to a larger scale.

In the shafting of a propeller which serves for the propulsion of a water or air craft the servomotor 1 is inserted between the intermediate shaft 2, which is connected to the propulsion plant, and the propeller shaft 3. Attached to the latter is the propeller, not shown, with blades adjustable in service. The servomotor 1 is supported in the bearing shells 4 and 5 connected to the casing bottom 6 and the upper part 7 of the casing, which are closed by the cover 8.

The upper bearing shell 5 carries the control casing 9 with the control valve 10 of the servomotor 1 and the small receiver piston 11 of the hydraulic operating system 12. The transmitting member of the system 12 is not shown; it determines the pressure in the system 12 and is situated, for instance, at the controls of the craft.

Where the shafts 2 and 3 leave the casing 6—8 sealing is provided by the stuffing-boxes 13 and 14. The pressure medium for the servomotor 1, usually pressure oil, is supplied and led off through the connecting branches 15 and 16, the passages 17 and 18 in the control casing 9 and in the upper bearing shell 5, according to the position of the control valve 10, and further through the annular grooves 19 and 20 in the bearing shell 4 and 5, passing from there through the passages 21 and 22 to the servomotor pistons in the casing of the servomotor 1.

The leakage oil from the bearing 4, 5 of the servomotor 1 collects in the sump 23, is drawn

in through the suction pipe 27 by the pump 24, which is designed for instance as a gear-type pump and driven through the helical gear wheels 25, 26 from the intermediate shaft 2, and is delivered through the pipe 28 into a container not shown in the drawing. A drain pipe down to a lower container might also be connected to the sump 23 in place of the pump 24.

In this way the servomotor casing 6—8 is unable to fill with pressure medium and cannot be loaded by the pressure of the pressure medium. Consequently the stuffing-boxes 13 and 14 are also relieved of all pressure and losses of pressure medium are practically impossible. Stuffing-boxes on the propeller shaft subjected to the pressure of the pressure medium are thus entirely dispensed with. The control parts are also completely protected against dirt, rust and damage.

In order to keep the sealing of the bearing 4, 5 intact if possible for years, wear is practically prevented by the weight of the casing 6—8, of the bearing 4, 5 and of the control parts 9 and 10 being entirely compensated. The springs 29, 30, which are mounted between the projecting pieces 31 on the casing element 6 and the foundation 32, are provided for this purpose. A pair of springs 29, 30 may be provided in one or two cross-sections of the casing 6—8. When there is only one pair of springs 29, 30, this is arranged in the plane in which lies the centre of gravity of the casing.

In order to prevent the casing from turning the pins 33, 34 are provided, and these can be adjusted, with a small clearance required for the spring effect, by means of the nuts 35. The loading of the springs 29, 30 can be accurately adjusted with the nuts 36. The servomotor 1 may have one or more pistons which move along the axis of the propeller shaft or are designed as rotary pistons. In both cases the adjusting member 48 in the shaft 3 can perform either a rotary movement or a longitudinal movement in the propeller shaft 3 to adjust the blades of the propeller.

Between reciprocating pistons and a rotary adjusting shaft 48 a worm gear with steep thread is arranged in a known manner. The adjusting linkage in the hub of the propeller between the member 48 and the propeller blades is designed in a known manner according to the movement of the adjusting member 48. The servomotor 1 is connected to the flanges of the shafts 2 and 3 and centred by means of the bolts 44 and 45.

Fig. 3.

In the servomotor 1 are the pistons 46 and 47, which are mounted on the adjusting rod 48 and supported against each other and against the fixing screw 51 by the distance sleeves 49 and 50. The pistons 46 and 47 run in liners 52 and 53 and are shut off and fixed by the cover 54 and the screwed sleeve 55. The liner 53 is integral with the partition 56.

The servomotor cylinder 1 rotates in the two-piece bearing with the lower shell 4 and the upper shell 5, which are held together by the bolts 57, Fig. 2. The control member 10 works in the bore 58 in collaboration with the pressure medium supply 15 to the space 59 and the pressure medium discharge 16 from the space 60, as do also the passages 17 and 18 leading to the servomotor 1, which are covered by the control edges 61 and 62 in the closed position of the control valve 10.

The passage 17 is in communication with the annular groove 19 in the bearing 4, 5. The passage 18 is in communication with the annular groove 20. From the annular groove 19 the pressure medium passes through the passage 21, the groove 63 in the liner 52 and the openings in the liners 52, 53 leading to the piston spaces to the left of the pistons 46 and 47, while the annular groove 20 communicates with the passage 22, to which is connected the groove 64 in the liner 52. From the groove 64 the pressure medium passes into the piston spaces lying to the right of the pistons 46, 47.

In a further bore in the casing 9 is the small piston 11, which acts as a receiver in the hydraulic system 12 and adjusts through the set screw 65 the slide piece 66 and the lever 67 in opposition to the force of the spring 68, the loading of which can be altered by means of the set screw 69. The lever 67 is connected through the link 70 to the control member 10 and through the link 71 to the segment-shaped slide piece 72, which is fitted in the groove 73 of the adjusting disc 74. The adjusting disc 74 is rigidly connected through the rods 75, which are screwed into the disc 76, to the pistons 46, 47 and the adjusting rod 48.

The linkage 72 to 76 forms the return mechanism of the control member 10 through the servomotor pistons 46, 47. The rods 75 are passed through the flange of the intermediate shaft 2; continuous slots in the driving shafts 2, 3 for returning the movement of the linkage 48 in the interior of the propeller shaft 3 to the control member outside of this shaft can be avoided by this means to some advantage, since such slots represent a considerable weakening of the propeller shaft.

The device works as follows: if an adjustment of the propeller blades is started in the hydraulic system 12 by a change of pressure, for instance a pressure rise, acting through the transmitter not shown in the drawing but provided at the controls, the small piston 11 moves to the left. The slide piece 66 turns the lever 67, the valve 10 is then moved to the left out of the closed position shown, so that pressure medium from the pipe 15 enters the passage 17 and the annular groove 19, passes through the passage 21 and the groove 63 to the left of the pistons 46, 47 into the servomotor cylinder, where it moves the pistons 46, 47 with the adjusting rod 48 to the right and brings about a turning of the propeller blades, for instance from the position for full speed ahead towards the neutral position. In the neutral position of the blades, in which the propeller exerts no thrust whatever, the pistons 46, 47 are in the middle position; the outermost

piston position on the right gives the other end position of the propeller blades, in the present example the position for full speed astern.

With the pistons 46, 47, the disc 76 and the adjusting ring 74 together with the slide piece 72 and the link 71 move to the right, so that the lever 67 turns about its upper extremity and returns the valve 10 towards the closed position shown. When the small piston 11 is brought to a standstill, the valve 10 will be moved to the right till the passages 17 and 18 are completely closed and will remain in this closed position. The pistons 46, 47 moving to the right force the pressure medium in the right-hand piston spaces through the groove 64, the passage 22, the annular groove 20 and the passage 18 into the space 60 and from there into the drain pipe 16.

If the valve 10 is displaced to the right out of the closed position shown, the passage 18 and with it the spaces to the right of the pistons 46, 47 is connected to the pressure medium supply 15, while the pressure medium from the spaces to the left of the pistons 46, 47 passes by the route indicated to the passage 17 and through the longitudinal passage 71 and the openings 78 to the space 60 and to the drain pipe 16.

The lubricating oil supply or the oil filling of the hub of the adjustable propeller is provided through the stuffing-box 14. The latter has a passage 79 which communicates with a lubricant tank arranged so high above the water level of the water craft that the hydrostatic pressure in the hub slightly exceeds the greatest hydrostatic pressure outside the hub. In the stuffing-box 14 is a lubricating groove 80, inserted opposite the passage 79, and the passage 81 in the propeller shaft is arranged in the same cross-section, so that even when the shaft turns filling is always possible from the pipe 79. The passage 81 runs into the passage 82 of the adjusting member 48, which is sealed off from the servomotor 1 by a packing 83. The passage 82 extends through the whole of the propeller shaft 3 to the hub of the propeller. On the underside of the stuffing-box 14 are two drain passages 84, which conduct into the interior of the casing 6 any lubricating medium leaking through the packing 14.

I claim:

1. For use in a controllable-pitch propeller assembly, a stationary casing, a shaft passing through said casing comprising a driving shaft portion, a driven hollow shaft portion and a tubular housing portion communicating internally with said driven hollow portion, all said shaft portions being connected in torque-transmitting relation to one another, a control linkage member arranged within said driven hollow shaft portion, packing elements carried in each end of said casing making a fluid tight seal with said shaft, a fluid-pressure servomotor having a reversibly-operable, pressure-moving member inside a pressure-fluid chamber within said housing portion, said pressure-moving member being arranged to activate said control linkage member, a stationary source of fluid under pressure located outside said shaft, a stationary sleeve surrounding said shaft, and passages contained in said shaft leading from the interior of said housing portion to the exterior of said shaft within said sleeve, said sleeve serving to transmit fluid under pressure from said source to said servomotor through said passages, said sleeve being inside said casing and spaced away from said packing elements.
2. In the combination of claim 1, fluid transmitting means including annular grooves inside

the sleeve, conduits in the shaft leading from said grooves to the pressure-fluid chamber of the servomotor, tubes leading from the outer walls of said sleeve to the source of fluid under pressure, and the conduits in the body of said sleeve leading from said grooves to said tubes.

3. In the combination of claim 2, a control member for introducing selectively the fluid under pressure to chosen portions of the servomotor pressure-fluid chamber, said control member being located inside the casing and including a valve chamber inserted in the fluid transmitting means and an operable valve member within said valve chamber.

4. In the combination of claim 1, a sump within the casing for collecting fluid leading past the sleeve, a fluid pump scavenging from said sump, a fluid receiver outside said sleeve and tubes connecting said pump to said receiver.

5. In the combination of claim 1, means for 20 relieving the shaft of at least a part of the weight

of the casing, said means consisting of elastic elements connecting said casing to fixed points of support.
